SWITCH UNIT FOR VEHICLE PARKING ALARM

Arthur G. Millerlei, 212½ N. 11th Ave.,
Evansville, Ind. 47712

Filed July 15, 1966, Ser. No. 3,083

Term of patent 14 years

(Cl. D26—13)

FIG. 1 is a perspective view of a switch unit for vehicle parking alarm showing my new design;

FIG. 2 is a side elevational view thereof; and

FIG. 3 is a front elevational view thereof.

The broken line representation of a portion of a vehicle in FIG. 1 is for purposes of illustration only.

I claim:

The ornamental design for a switch unit for vehicle parking alarm, as shown and described.
